UNITED STATES PATENT OFFICE.

WILLIAM A. DOBSON, OF BRIDGEPORT, CONNECTICUT, ASSIGNOR TO UNDERWOOD
TYPEWRITER COMPANY, OF NEW YORK, N. Y., A CORPORATION OF DELAWARE.

TYPEWRITING MACHINE.

Application filed December 5, 1922. Serial No. 605,006.

The present invention relates to typewriting machines. As to certain features thereof, the invention more particularly relates to machines of the so-called portable class, 5 and to machines in which the platen carriage has its movements in letter-feed and return directions on a case-shift frame; the latter being guided by the main frame in its movements between case positions.

10 Machines of the portable class not only receive rough treatment in being conveyed from place to place by the user, but are often delivered by express or parcel post, and in the course of such delivery are thrown violently about. Because of the inertia of the carriage and shift-frame, such treatment of the machine often causes the screws, and other elements which hold the parts together, to be strained and distorted, and the 15 parts to be jammed or thrown out of true alignment or registry.

One feature of the invention is the provision of means for adjusting the elevation or other setting of the carriage on the frame 20 properly to present the platen to the types, or for other reasons; while nevertheless maintaining the usual roller bearing of the carriage on its supporting rail. In the preferred form of the invention, I effect this object by journaling the roller in an arm 25 pivotally connected to the carriage (instead of, as heretofore journaling the roller directly on the carriage), and by employing an adjusting screw on the carriage in engagement with the arm a micrometrical adjustment is provided for swinging the arm on its pivot; thereby using the roller on its rail as a fulcrum on which the arm, as a lever, may lift and lower the carriage.

30 The case-shift frame must be guided, without undue lateral play, in its movements between case positions. The inertia of the carriage, whether by reason of shock received in the handling of the machine, or of shock due to the movement thereof by the drum spring, has heretofore resulted in uncentering of the shift-frame, jamming of the same on its guides, and distortion of screws or other retaining parts.

35 Another feature of the invention is the

provision of means for buttressing the setting of the shift-frame, on a guide rail therefor, such that the setting may not be disturbed, or screws, or other attachments, strained, by shocks due to the jumping of 55 the carriage by its drum spring, or to rough handling of the machine.

In the preferred form of the invention, the shift-frame has a roller bearing on the right-hand side of a rail which guides the shift-frame in its movements between case positions. A slide which carries the roller is adjustable on the shift-frame perpendicularly to the rail, and, for this purpose, has a screw-and-slot engagement with the shift-frame, whereby the slide and roller may be locked in adjusted positions. For relieving this screw of strains, I provide a wedge movable on the case-shift frame, into position behind, and tightly against, the slide, after 60 the latter has been set.

A further feature of the invention is a novel, efficient and simple locking device for the case-shift lever; which device is certain in its locking action, and is releasable with certainty upon mere pressure on the shift-key-lever when return to lower-case position is desired.

Other features and advantages will hereinafter appear.

In the accompanying drawings.

Figure 1 is a top plan view of so much of the mechanism of an Underwood standard portable typewriter as involves the present invention.

Figure 2 is a view, in front elevation, taken on the line 2—2 of Figure 1.

Figure 3 is a view, in side elevation, partly cross-sectional, taken on the line 3—3 of Figure 1.

Figure 4 is a view, in side elevation, of the upper-case shift-key and lock mechanism therefor.

Figure 5 is a detail view in front elevation, showing the means for holding against displacement the rail on the shift-frame on which the forward part of the carriage runs.

Figure 6 is a detail view, in front elevation, partly cross-sectional, on the line 6—6

of Figure 3, of the adjustable mounting for the rail on the shift-frame which supports the forward part of the carriage.

The main frame 10 of the machine is set within and screwed to an outer ornamental frame 11. The main frame comprises side pieces 12 tied together by cross-pieces 13 and 14, one in front of the other. The platen case-shift frame, comprising right and left hand side plates 15 and a rear cross-plate 16, is mounted for movement up and down, between three case positions, in the main frame. The case-shift frame is supported and guided in its case-shift movements by means of right and left hand arms 17, fast at their rear ends to a rock-shaft 18 pivotally mounted in the main frame, and having at their forward ends pins 19 set in recesses 20 in the forward lower edges of the side plates 15 of the case-shift frame, and on which pins the forward portion of the case-shift frame is supported. For further supporting and guiding the case-shift frame in its case-shift movements are another pair of arms 21 pivoted at 22 to the side plates of the main frame at the rear thereof, and pivotally connected at their forward ends at 23 to the forward upper portions of the side plates 15 of the case-shift frame.

The side plates 15 of the case-shift frame, at their lower edges, have flanges 24 offset inward thereon, and, when the case-shift frame is in its normal or lower-case position, it is supported, by means of these flanges 24, on screws 25 adjustably set into ears 26 on brackets 27, secured by screws 28 to the rear cross-piece 14 of the main frame. The brackets 27 have also upstanding arms 29 offset at 30 at their upper ends to form ears which carry adjustable screws 31, also for engagement with the flanges 24 to determine the upper-case position of the shift-frame. The middle-case position of the shift-frame is determined by screws 32 adjustably set into ears or offsets 33 on the upper ends of arms 34, pivoted at 35 to the main frame, one at each side thereof. When the shift-frame is thrown by the middle-case key, in-turned ears or offsets 36, formed on the lower edges of the side plates 15 thereof, engage the screws 32, and the case-shift frame is thereby arrested in middle-case position. By means presently to be described, the stop arms 34 are thrown to move the stop-screws 32 from the path of the ears 36 of the case-shift frame when the latter is to be thrown to upper-case position. The arms 34, one at each side of the machine, form with the cross-piece 37 a bail which is normally held in Figure 3 position, and which is returned to Figure 3 position by a spring, not shown, but which connects the cross-piece 37 at one end thereof to one of the side pieces of the main frame.

For throwing the case-shift frame to middle-case position a key 38 is employed. This key is on a lever 39, pivoted at 40 to a bracket 41 fast to the cross-piece 13 of the main frame. Rearward of the pivot 40 the lever 39 has an arm 42 which underlies an offset 43 on the right-hand side of an arm 44 fast to the rock-shaft 18. Consequently, depression of the key 38 causes the arm 42 to rock the arm 44 upward and to turn the rock-shaft 18 accordingly. The arms 17, which support the case-shift frame, and which are also fast to the rock-shaft 18, are, therefore, also rocked upward, causing the case-shift frame to rise until the ears 36 on the side plates thereof engage the stop-screws 32 and determine the middle-case position. A spring 45, fast at one end to the lever-arm 42 and at its other end to a bracket 46 secured to the cross-piece 13, returns the middle-case-shift lever to normal position, as determined by an adjustable stop-screw 45^a on the bar 13, when free to do so. This lever is, however, provided with a locking device for holding it in middle-case position when desired. The locking device comprises a lever 47 pivoted at 48 to the shift-lever 39; the lever 47 having at its forward end an upright 50 terminating in a finger-piece 51, and having at its rearward end an arm 52 which forms a bell-crank therewith. The lock-lever 47 is normally held in, and is returned to, its Figure 3 position by means of a spring 53 secured at one end to the lock-lever arm 52 and at its other end to the shift-key lever 39.

An offset 54 on the forward end of the lever 47, by engagement with the under edge of the shift-key lever 39, determines the throw of the lock-lever under the action of the spring 53; and an offset 55 on the rear edge of the upright 50 on the front of the lock-lever, by engagement with the upper edge of the shift-key lever 39, causes the lock-lever to pick up and carry with it the shift-key lever after the finger-piece 51 on the lock-lever 47 has been depressed a sufficient distance. A bracket 56, secured to the main frame, has a slotted plate 57 at the upper end thereof to receive the lock-lever arm 52, and this slot terminates at a shelf 58, under which a shoulder 59 on the lock-lever may pass, and by means of which the lock-lever may be held down and the shift-key lever held in depressed or middle-case position. When the case-shift lever is depressed by the key 38, it carries with it the lock-lever 47, but does not effect sufficient movement of the lock-lever to bring the shoulder 59 under the holding shelf or detent 58. When, however, the finger-piece 51 of the lock-lever is depressed, that lever has a movement which is independent of the shift-key lever until the offset 55 reaches the shift-key lever, and then has a move-

ment with the shift-key lever until the forward edge of the lock-lever arm 52 strikes against the shelf 58. Further pressure at this time upon the finger-piece 51 causes the 5 arm 52 of the lock-lever to force down the shift-key lever in such manner that the shift-key lever is cleared of the offset 55 on the lock-lever. As the shift-key lever is thus forced down, drawing with it the lock-lever arm 52, the shoulder 59 on the latter presently gets below the shelf or detent 58, and the clearance at this time between the offset 55 of the lock-lever and the upper edge of the shift-lever permits a rocking 10 movement of the lock-lever relative to the shift-lever, to permit the shoulder 59 to be brought under the shelf or detent 58, where it is held by friction due to the tension of the return spring 45 of the shift-lever. The 15 spring of the shift-lever and of its connections is, however, such that, when pressure is applied to the key 38, the frictional hold of the lock-lever on the shelf or detent 58 is released, so that the lock-lever, under the 20 action of its spring 53, may be cleared of the detent 58, and the case-shift frame and case-shift lever allowed to return to normal position.

For moving the case-shift frame to upper-case position, there is provided a key 60 on the forward end of a lever 61, pivoted at 62 to the bracket 41. Rearward of the pivot 62 of the lever 61 is extended an arm 63, which underlies and is adapted to have a wiping engagement with a curved block 64 pinned to the left hand side of the arm 44. The effective arm 63 on the upper-case-shift lever 61 is longer than the effective arm 52 on the lower-case-shift lever, and effects a 25 throw of the case-shift frame sufficient to bring the flange 24 thereof to the stop-screw 31 which determines the upper-case position.

For throwing the middle-case stop-arms 34 and screws 32 out of the path of the stops 36 on the shift-frame, when the upper-case-shift lever is actuated, there is secured to the cross-piece 37, on which the arms 34 are carried, an arm 65 having on its upper end a roller 66. This roller lies in the path of a curved lug or cam 67, formed as an ear on a bracket 68 secured by screws 69 to the side of the upper-case-shift lever 61. The parts being in the normal or Figure 3 position, depression of the key 60 causes the lug 67 50 to depress the arm 65 and rock the bail, of which the arms 34 form part, around its pivot 35 in such direction as to throw the stop-screws 32 on the arms 34 forward of the stops 36 on the case-shift frame. The 55 shift-lever 61 is supported in normal position by the roller 66 and arm 65.

The upper-case-shift lever is also provided with a device for locking it, and the case-shift frame, in upper-case position. This locking device comprises a lever 70, pivoted

at 71 to the case-shift lever 61. At its forward upper end, the lock-lever 70 carries a finger-piece 72; and, rear of its pivot 71, is extended in the form of an arm 73. The locking device for the upper-case-shift lever 70 also comprises an arm 74, similar in some respects to the arm 52 which locks the middle-case lever, but which is not an integral part of the lock-lever 70. The lock-arm 74 is pivoted at 71 independently of the lock-lever 70. A finger 75, forming a lower extension of the arm 74 below the pivot 71, is, however, connected with the arm or tail 73 of the lock-lever 70 by a spring 76; so that, when the finger-piece 72 is depressed to rock the arm 73 80 rearward, the spring 76 causes the arm 74 to swing forward as a unit with the lock-lever 70 until the arm 74 strikes against a shelf or detent 77, similar to the shelf or detent 58, on the upper end of the bracket 56. The 85 spring 76 thereupon yields to permit of further movement of the lock-lever 70 around its pivot 71 to bring a finger 80, thereon, to the shift-lever. Continued depression of the key 72 causes the shift-lever to be depressed 90 by the lock-lever 70, carrying with it the arm 74, which now slides down along the shelf 77, until a shoulder 81 on the arm 74 is free to be snapped under the shelf 77 by the tensioned spring 76. This occurs as the 95 shift-lever completes its case-shift movement.

If the fingerpiece 72 be then released, the parts will nevertheless remain in upper-case position, by reason of frictional engagement 100 of the shoulder 81 with the ledge or detent 77, due to the weight of the case-shift frame and carriage. To unlock the parts, it is simply necessary to press upon the key 60. Because of the yield of the parts, this pressure relaxes the pressure of the shoulder 81 on the ledge or detent 77 sufficiently to permit a spring 78, connected at one end to the arm 74 and at its other end to the shift-lever 61, to return the arm 74 to Figure 4 position. 110 The arm 74, in moving to Figure 4 position, acts through the spring 76, to return the lock-lever 70 to its normal position with respect to the shift-lever, as determined by engagement of an offset 79, on the lock-lever, with 115 the under edge of the shift-lever. The relative strength of the springs 76 and 78 is such that normally, and except when the arm 74 is pressed against the shelf 77, the spring 76 will hold the arm 74 against a stop 82 on the lock-lever 70. Instead of operating the shift-lever by means of the lock-lever finger-piece, the shift-lever may be operated by its key 60; and, while it is depressed, the finger-piece 72 may be depressed to rock the lock-lever 70 with respect to the shift-lever in 120 such manner as to tension the spring 76 and throw the lock-arm 74 forward to cause the shoulder 81 thereof to engage under the ledge or detent 77. 125

A platen 83 is revolvably mounted in the side plates 84 of the carriage, which is movable in letter-feed and return directions on the case-shift frame, but which is movable as a unit up and down with the case-shift frame from one to another case position. The side plates 84 are connected by a cross-piece or tie 85 at the rear, and by another cross-piece or tie 86 below the platen. The cross-piece 86 is supported by roller-bearings 87 on a rail or runway 88 secured to the case-shift frame. A roller 142, carried by a bracket-arm 143, secured to the cross-piece 86, engages the under side of the rail 88 to hold the forward part of the carriage to the rail 88, and thus obviates any tendency of the cross-piece 86 to overrun the roller-bearings 87 toward the rear of the machine, and consequent displacement of the platen-carriage. The carriage cross-piece 85 carries a roller 89, by means of which the carriage is supported at its rear on a rail 90 formed on the upper edge of the rear cross-piece 16 of the case-shift frame.

It is a feature to have the case-shift element 88 adjustable so that the platen may be made truly parallel with the printing plane of the types, that is, so that the platen may be trued relatively to the printing types, whereby the types (arrested by the usual abutment when in printing position) may strike with equal force on the platen throughout its length. To this end, the rail 88 is not made fast directly to the side plates 15 of the case-shift frame, but is attached at its ends, by means of screws 91, to a flange or arm 92 forming part of a U-shaped piece or slide 93 set against the inside face of the corresponding side plate 15 of the case-shift frame. A screw 94, passing through a horizontal slot 95 in the side plate of the case-shift frame, threads into the central member 96 of each U piece. When the screws 94 are loosened, the U pieces, with the rail 88 attached thereto, may be adjusted forward and rearward, and, when so adjusted, and the rail 88 is parallel to the rail 90, the rail 88 will be held in such adjusted position upon tightening of the screws 94. For effecting the adjusting movement of the U pieces and attached rail 88, the forward flanges or arms 97 of the U pieces are in threaded engagement with screws 98. These screws, by means of their heads 99 and collars 100, are held fast to ears 101 stamped or turned inward out of the side plates 15. Upon revolution of the screws 98 in one or the other direction, therefore, the rail 88, at one or the other, or both ends, is moved forward or backward. Lock-nuts 102 on the screws 98 maintain the adjustment. To provide guideways for the U sections 96 and to assure horizontal movement thereof, bosses 103, preferably four of them, as shown in Figures 3 and 6, are pressed or sheared inward out of the body of the side plates of the shift-frame.

In order that the rear portion of the carriage may be adjustable upward and downward with respect to the rail 90, so as to bring the platen forwardly and rearwardly to proper position with respect to the types 104, the following means is provided. The axle of the roller 89 is not directly mounted upon the rail 85. As shown in Figure 2, the axle 105 of the roller 89 is revolvably supported in an arm 106 pivotally attached at 107 to an ear 108 depending from the forward edge of the rail 85. Adjustable connection of the arm 106 to an ear 109 is formed by a slot 110 in the arm 106 and by a screw 111 which passes through the slot 110 and threads into the ear 109. When the screw is loosened, the arm may be lifted or lowered to adjusted position, and, when the screw is tightened, is held in such adjusted position. For effecting the adjusting movements, there is a screw 112 which is threaded through the cross-piece 85 and which is adapted to bear upon an ear or offset 113 on the arm 106. When the screw is withdrawn upward, the weight of the carriage causes the arm 106 and roller 89 to follow the screw. When the screw is turned downward against the ear 113, the arm 106 and roller 89 are pressed down and the cross-piece in rear of the carriage correspondingly elevated on the rail 90. A lock-nut 114 holds the screw 112 in adjusted position. It will be understood that the roller 89 at all times rests upon the rail 90, and that the axis of the roller serves as a fulcrum around which the arm 106, as a lever, lifts or lowers the carriage as the screw 112 is turned. For anchoring the carriage to the rail 90, so that the same may not be lifted clear thereof, the arm 106 has an ear or lug 115 turned under the rail 90 from the lower edge of the arm.

As a guideway or guide for the shift-frame in its up-and-down movements on the main frame, there is attached to the rear cross-piece 116 of the outside or ornamental frame 11 a vertical arm or rail 117. This rail is secured by screws 118 to a boss 119 on the inner face of the cross-piece 116. The arm or rail 117 is further anchored against displacement on the boss 119 by ears 120, which are formed on the arm 117 and which embrace the boss 119. A roller 122, carried by a bracket 123 secured to the inner face of the rear cross-piece 16 of the shift-frame, is adapted to bear against the right-hand side of the arm or rail 117; and an ear or flange 124, on the left-hand side of the rail 117, struck out of the cross-piece 16, defines, with the roller 122, the runway in which the arm or rail 117 has movement with respect to the case-shift frame in the case-shift movements of the latter. Whereas the roller 122 is intended to bear upon

the rail 117, the rail 117 will ordinarily not bear upon the ear 124; the latter serves rather as a guard than as a bearing for the rail 117. For correctly positioning the roller 122 with respect to the rail 117, the bracket 123, on which the roller 122 is journaled, is longitudinally adjustable on the shift-frame cross-piece 16. This adjustability is obtained by having horizontal slots 125 in the cross-piece 16 and by having screws 126 passed through these slots and threaded into the bracket 123. When the screws are loosened, the bracket 123, with the roller, may be adjusted perpendicularly to the edge 10 of the rail 117; and, when such adjustment has been effected, the screws may be tightened to hold the bracket and roller in adjusted position.

The usual carriage drum-spring (not shown) tends to throw the carriage to the left, and the inertia of the carriage, when thrown under the impulse of the drum-spring, tends to displace or force the shift-frame leftward with respect to the main frame. As the roller 122 bears upon the right-hand side of the guide-rail 117, such leftward displacements of the shift-frame tend to cause the roller to be dislocated by the rail 117, or to be jammed with respect thereto. The screws 126 tend to resist this action, but these screws sometimes fail to hold, or themselves become distorted; and it is desirable to relieve them of these strains. For this purpose, and also for adjusting the bracket 123, there is provided, at the right-hand side of the bracket 123, a block 127. When this block is in place, it abuts the end of the bracket 123 and holds the same fixed against rightward movement. The block 40 127 is in the form of a wedge, and the end of the bracket 123, which abuts the block, is cut at the same incline as the wedge surface of the block. The block is adjustable up and down upon the inner face of the cross-piece 16 of the shift-frame, thereby providing simple means for holding the bracket 123 and for obtaining proper adjustment of said bracket to bring the roller 122 into co-operative relation with the rail 117. 45 For this purpose, there is provided a vertical slot 128 in the cross-piece 16, and a screw 129 passes through this slot and threads into the block. When the screw is loosened, the block may be moved up and down, and, when tightened, the block is held in place. In fixing the parts, the block is held up while the position of the bracket 123 and roller 122 is determined and fixed by the screws 126. Thereupon the block is forced down until it is wedged firmly against the end of the bracket 123, after which the screw 129 is tightened.

As hereinbefore described, the rail 88, on which the forward part of the carriage rides, is held to the shift-frame by means of the

screws 91. It has been found that, in spite of the screws 91 or other screw attachments, the rail 88 frequently gets knocked up or down from its true position on the shift-frame; usually because of inertia of the carriage and the shocks to which the machine is subjected in transportation. To relieve the screws 91 and other connections of the rail 88 to the shift-frame of the work of meeting such shocks, and to prevent distortion and displacement of the rail and its connections, due to such shocks, the following device is provided.

A bracket 130 (see Figure 5) is secured by a screw 131 to the front face of the rail 88 at each end thereof. Each bracket is horizontally slotted as at 132, and the screw 131 passes through the slot and threads into the rail. When the screw is loosened, the bracket may be moved longitudinally of the rail. Each bracket carries, or has as part thereof, a block 133 which is set against the under edge of the rail between the latter and a shoulder 134 formed in the corresponding side plate 15 of the carriage-shift-frame. As shown in Figure 5, the under surface of the block is tapered as at 135, so that, when the screw 131 is loosened, the block may be moved so as to be wedged between the shoulder 134 of the plate and the rail 88, thereby relieving the screws 91 and other connections of the rail to the shift-frame of strains due to downward pressure of the carriage. The rail is also blocked against upward movement. For this purpose, there is at each side of the machine a bracket 136 secured to the shift-frame by a screw 137 and also held against upward movement on the shift-frame by an ear 138, which is struck upward from the top edge of the shift-frame and against which the upper edge of the bracket 136 abuts. The bracket 136 has a finger or tongue 139 thereon, which is extended rearward to overlie and bear upon the upper edge of the rail 88. As shown in Figure 3, this finger 139 may be slightly offset downward at its end, or made thinner at its end, as at 140, to provide ample clearance for the forward edge or lip of the carriage cross-piece 86. The side plates 15 of the case-shift frame are slotted where they receive the screws 137; and these slots, and the ears 138, are at a downward and rearward incline, so that, if the screws 137 are loose, the brackets 136 and fingers 139 will be pressed or cammed down on the top edge of the rail 88 upon rearward movement of the brackets 136. After the fingers 139 have been thus firmly set upon the rail 88, the screws 137 are tightened to hold the fingers in place. The fingers 139, as shown in Figures 3 and 5, therefore, relieve the screws 91 and other connections of the rail 88 of strains tending to force the rail upward.

It has been hereinbefore stated that a spring, not shown, by drawing on the bail cross-piece 37, returns the stop-arms 34 to normal position when the upper-case-shift key is released. It occasionally happens, particularly if the hand is on the platen-knob, that the spring mentioned throws the arms 34 to normal position before the stop-ears 36 on the shift-frame have had an opportunity to pass the ears 33 on the stop-arms 34. If this should happen, the case-shift frame, instead of returning to normal position, would come to rest with the ears 36 thereof on top of the ears 33 of the stop-arms 34. To prevent such an occurrence, the ears 36 on the shift-frame have lips 144 depending from the forward edges thereof. These lips are of a length sufficient, when the case-shift frame is in upper-case position, to cross the path of rearward movement of the ears 33 on the arms 34; thereby preventing passage of the ears 33 under the ears 36, and assuring return of the case-shift frame to lower-case position without being interfered with by the stop-arms 34.

Variations may be resorted to within the scope of the invention, and portions of the improvements may be used without others.

Having thus described my invention, I claim:

1. In a typewriting machine, a platen, a case-shift frame for the platen, a key and lever for shifting the former, and means for locking the shift-lever with the frame in shifted position, including a lock-lever and a key therefor, pivoted to the case-shift lever, an arm or dog mounted on the pivot of the lock-lever, a stop engageable by the arm or dog, and a spring connecting the lock-lever directly to the arm or dog to cause the arm or dog to move, as a unit, with the lock-lever until the arm or dog strikes the stop and thereupon to yield to permit further movement of the lock-lever with the shift-lever.
2. In a typewriting machine, a platen, a case-shift frame for the platen, a key and lever for shifting the frame, and means for locking the shift-lever with the frame in shifted position, comprising a lock-lever, and a key therefor, pivoted to the case-shift lever, an arm or dog pivoted to the case-shift lever and movable thereon relatively to the lock-lever, a stop engageable by the arm or dog, a spring connecting the lock-lever and the arm or dog to cause the arm or dog to move with the lock-lever until the arm or dog strikes the stop and thereupon to yield to permit further movement of the lock-lever with the shift-lever, and a stop on the lock-lever against which the arm or dog sets until the arm or dog strikes the first-mentioned stop.
3. In a typewriting machine, a platen, a case-shift frame for the platen, a key and lever for shifting the frame, and means for locking the shift-lever with the frame in shifted position, including a lock-lever and a key therefor, pivoted to the case-shift lever, an arm or dog mounted on the pivot of the lock-lever, a stop engageable by the arm or dog, a spring connecting the lock-lever directly to the arm or dog to cause the arm or dog to move, as a unit, with the lock-lever until the arm or dog strikes the stop and thereupon to yield to permit further movement of the lock-lever with the shift-lever, and a spring connecting the arm or dog to the shift-lever to automatically return the arm or dog and lock-lever to normal position, when said arm or dog is released from the stop.
4. In a typewriting machine, a platen, a case-shift frame for the platen, a key and lever for shifting the frame, means for automatically returning the shift-lever to normal position when the shift-lever is released, and means for locking the shift-lever with the frame in shifted position, including a lock-lever and a key therefor, pivoted to the case-shift lever, an arm or dog mounted on the pivot of the lock-lever and movable on said pivot relatively to the lock-lever, a stationary stop engageable by the arm or dog, said lock-lever and said dog each including an extension on the opposite side of said pivot, a stop carried by the lock-lever, a spring connecting the extensions to cause the arm or dog to engage the stop of said lock-lever and to move with the same, as a unit, until the arm or dog strikes said stationary stop and thereupon to yield to permit further movement of the lock-lever with the shift-lever while the arm or dog slides on the side of the stop; the arm or dog having a shoulder to be automatically snapped under the stop, by the spring, as the shift-lever completes its case-shifting operation, and to be held frictionally to the stop, on release of the key, by the means for returning the case-shift lever to normal position, and a spring for throwing the arm or dog from the stop when such frictional hold is relaxed by pressure on the case-shift lever key at a time when the lock-lever key is released.
5. In a typewriting machine, a platen, a case-shift frame for the platen, a lever for throwing the case-shift frame to a middle-case position, a stop for determining the middle-case position of the shift-frame, a lever for throwing the case-shift frame to an upper-case position, a curved lug on the upper-case shift-lever, and an arm on the middle-case stop having a roll thereon engageable by the curved lug to rock the stop to ineffective position when the upper-case shift-lever is operated.
6. In a typewriting machine, a main frame, a case-shift frame movable between case positions on the main frame, a platen-

carriage mounted to run on the case-shift frame, a guide rail for the case-shift frame on the main frame, a roller on the case-shift frame for engagement with one side of the rail, a guard for the opposite side of the rail, a block or slide carrying the roller and having a screw-and-slot engagement with the case-shift frame for adjustable setting of the roller against the rail, and means for blocking the roll-carrying slide, after the same has been secured in place, to reinforce and protect the attachments of the slide to the case-shift frame.

7. In a typewriting machine, a main frame, a case-shift frame movable between case positions on the main frame, a platen-carriage mounted to run on the case-shift frame, a guide rail for the case-shift frame on the main frame, a bearing piece on the case-shift frame for engagement with one side of the rail, a guard for the opposite side of the rail, means supporting the bearing piece for adjustment thereof with respect to the rail, means for securing the support in adjusted position, and means for blocking the bearing-piece support to reinforce and protect the attachments thereof.

8. In a typewriting machine, a main frame, a case-shift frame movable between case positions on the main frame, a platen-carriage mounted to run on the case-shift frame, a guide rail for the case-shift frame on the main frame, a bearing-piece on the case-shift frame for engagement with the rail, means supporting the bearing-piece for adjustment thereof with respect to the rail, means for securing the bearing-piece in adjusted position, and means for adjusting and then blocking the bearing-piece to reinforce and protect the attachments thereof, said blocking means including a wedge on the case-shift frame movable behind, and into sliding engagement with, the bearing-piece to adjustably move the same toward said rail before said bearing-piece is secured in adjusted position.

9. In a typewriting machine, a main frame, a case-shift frame movable between case positions on the main frame, a platen-carriage mounted to run on the case-shift frame, a guide rail for the case-shift frame on the main frame, a bearing piece on the case-shift frame for engagement with the rail, means supporting the bearing piece for adjustment thereof with respect to the rail, means for securing the support in adjusted position, and means for blocking the bearing-piece support to reinforce and protect the attachments thereof, said blocking means comprising a wedge having a screw-and-slot engagement with the case-shift frame to be movable behind, and into engagement with, the bearing-piece support after the latter is secured in adjusted position, and to be locked in place by the screw.

10. In a typewriting machine, a platen-carriage, a V-shaped lower rail providing a lower raceway, one side of the V facing toward the front of the machine, rollers in said raceway, an upper V-shaped rail on the platen-carriage and providing an upper raceway for said rollers, a bracket attached to the platen-carriage, and anti-friction means carried by said bracket and disposed around the lower rail in engagement with the front-facing side of the lower rail, whereby to slidingly hold the platen-carriage to said lower rail and to prevent the platen-carriage from being displaced toward the rear of the machine.

11. In a typewriting machine, type-bars and types thereon, a platen, a platen-carriage, a rail on which the carriage runs, a roller for supporting the carriage on the rail, an arm pivoted to the carriage and carrying the roller, and means for adjusting the arm up and down to adjust the position of the platen with respect to the types; the arm having a lip thereon offset under the rail for holding the carriage to the rail.

12. In a typewriting machine, a platen case-shift frame, a rock-arm for lifting the same, an offset on one side of the arm, a lever engageable with the offset for rocking the arm to throw the case-shift frame to one case position, a rounded block on the other side of the arm, and a lever adapted to have a wiping engagement with the block to rock the arm to throw the case-shift frame to another case position.

13. In a typewriting machine, a case-shift frame, a lever for shifting the frame to a middle-case position, an ear or lug on the case-shift frame, an arm engageable by such ear or lug to arrest the case-shift frame in middle-case position when the middle-case-shift lever is operated, an upper-case-shift lever, means whereby the upper-case-shift lever throws the middle-case stop-arm out of the path of the ear or lug on the case-shift frame to permit movement of the case-shift frame to an upper-case position when the upper-case lever is operated, means for returning the middle-case stop-arm to normal position when the upper-case-shift lever is released, and means for preventing the middle-case stop-arm from crossing the path of the ear or lug on the case-shift frame, when the upper-case-shift lever is operated, until after the ear or lug on the case-shift frame has passed the stop on the middle-case stop-arm, said last-named means being carried by the case-shift frame.

14. In a typewriting machine, a case-shift frame, a lever for shifting the frame to a middle-case position, an ear or lug on the case-shift frame, an arm engageable by such ear or lug to arrest the case-shift frame in middle-case position when the middle-case-shift lever is operated, an upper-case-shift

lever, means whereby the upper-case-shift lever throws the middle-case stop-arm out of the path of the ear or lug on the case-shift frame to permit movement of the case-shift frame to upper-case position when the upper-case lever is operated, means for returning the middle-case stop-arm to normal position when the upper-case-shift lever is released, and a lip or boss depending from the ear or lug on the case-shift frame to block the return of the middle-case stop-arm to normal position until after the ear or lug on the case-shift frame has passed the stop on the stop-arm on the return movement of the case-shift frame to normal position.

WILLIAM A. DOBSON.
